UNITED STATES PATENT OFFICE.

GEORGE VUILLE, OF SHELBY, OHIO.

HINGE CHECK.

1,423,784.

Specification of Letters Patent. Patented July 25, 1922.

Application filed March 2, 1921. Serial No. 449,024.

To all whom it may concern:

Be it known that I, GEORGE VUILLE, a citizen of the United States, and a resident of Shelby, in the county of Richland and 5 State of Ohio, have invented certain new and useful Improvements in Hinge Checks, of which the following is a specification.

My invention relates to hinge checks for double swinging doors, and a purpose of my 10 invention is the provision of a hinge check which is operable to permit of the ready opening of the door in either direction, maintaining the door in a 90° open position, and automatically closing the door when 15 moved from such angular position. Furthermore, my invention provides a hinge check which includes fluid control means for the closing of the door, such means being operable to effectively retard this closing action irrespective of the angle which 20 the door occupies when it is released.

I will describe one form of hinge check embodying my invention and will then point out the novel features thereof in 25 claims.

In the accompanying drawings:

Figure 1 is a fragmentary view showing in side elevation a door frame and double swinging door having applied thereto one 30 form of hinge check embodying my invention.

Figure 2 is a view showing in side elevation a finish plate adapted to be applied to the door for housing the hinge check.

Figure 3 is a vertical longitudinal sectional view of the hinge check shown in Figure 1 with the parts thereof in the proper positions when the door is in open position.

Figure 4 is a detailed perspective view of the stationary sleeve embodied in the hinge check shown in Figures 1 and 2.

Figure 5 is a view similar to Figure 4 showing the rotatable cam embodied in the 45 hinge check.

Figure 6 is a view similar to Figure 5 showing the reciprocating cam embodied in the hinge check.

Figure 7 is an enlarged detail view showing 50 partly in side elevation and partly in vertical section the retarding means comprised in the hinge check.

Figure 8 is a view similar to Figure 7 and taken at right angles to the latter.

55 Figure 9 is a transverse sectional view taken on the line 9—9 of Figure 8.

Figure 10 is a transverse sectional view taken on the line 10—10 of Figure 3.

Similar reference characters refer to similar parts in each of the several views.

Referring specifically to the drawings and particularly to Figure 3, the hinge check in its present embodiment comprises a floor plate P upon which is sustained a sleeve S which threadedly receives the lower end of a barrel B. In superimposed relation with respect to the sleeve S is a rotatable cam K, and interposed between the confronting edges of the sleeve and cam are roller bearings 15 mounted in raceways formed in the 60 edges of the sleeve and cam. The cam K is provided with laterally disposed arms 16 that are adapted to be secured to the door so that the cam bodily rotates with the door when the latter is swung to open position in 65 either direction. Arranged above the cam K is a reciprocating cam K', the lower edge of the cam K' and the upper edge of the cam K being so formed as to provide helical grooves 17 arranged in quadruple in oppositely disposed intersecting pairs, as shown in Figures 5 and 6. Each grooved helix extends through a quadrant to a point of intersection to an adjacent helix, the two adjacent helices being at opposite inclinations. The lower walls of the grooves on the upper edges of the cam K are at their 70 upper point of intersection notched as indicated at 17 to provide a resting place for the lower point of intersection of the upper 75 walls of the grooves, the reciprocating cam K' occupying this position in the open position of the door whereby the door may be retained in such open position. The upper edge of the reciprocating cam K' is formed 80

in an intersecting pair of helical cam surfaces 18 which are adapted to be engaged by a roller 19 (Figure 1) adapted to be carried by the door for restricting the upward movement of the cam K'. These cam surfaces 18 have their lower ends disposed below the upper edge of the remaining portion of the cam so as to provide shoulders 20 against which the roller 19 is adapted to abut when the door is in either of its extreme positions.

As shown in Figure 3, the barrel B is loosely embraced by the cams K and K' and serve to sustain these cams in position to permit of their reciprocating and rotary motions. Internally of the barrel B is arranged a container C which is formed at its lower 105

end with a threaded collar 21 that has threaded engagement with the walls of a suitable opening formed in the floor plate P. As shown in Figure 7, this container 5 C is formed of a main tubular section 22 and a top collar section 23 which is threadedly associated with the main section and between which is interposed a packing disc 24 that serves to hermetically seal the upper 10 end of the container. Within the lower end of the container C is positioned a pair of integrally formed cylinders D and D' having their lower or closed ends formed with a screw plug 25 which threadedly engages 15 the reduced end of the container. The plug 25 is formed with tool receiving recesses 25^a to permit of the rotation of the plug within the container and to thereby effect a restricted vertical adjustment of the cylinders 20 D and D' for a purpose which will be hereinafter described. As shown in Figure 8, the cylinders D and D' are formed adjacent their lower ends with ports 26 and 26^a, respectively, controlled by a cam valve 27 25 formed on the end of a screw threaded spindle 28 threadedly fitted in the container in the manner clearly shown in Figures 7 and 9. These ports 26 and 26^a are in communication with a channel 29 formed on the 30 periphery of the casing including the cylinders D and D', such channel in turn effecting communication between the upper part of the container and the ports so that with the valve 27 in open position any fluid 35 contained in the cylinders will be free to pass into the container at a point above the cylinders. As shown in Figures 8 and 9, the cylinder D is formed intermediate its ends with a port 30 which communicates with a 40 channel 31 that extends to the upper end of the cylinder and thus forms communication between the upper part of the container and the cylinder D for a purpose which will be hereinafter described. 45 Adapted to work within the cylinders D and D' are pistons T and T', respectively, formed on the lower ends of rods 32 and 32^a which are slidably fitted within suitable 50 openings formed in the collar section 23. The rods in turn are rigidly connected to a guide 55 plunger G which as shown in Figure 3 is slidably fitted within a thickened portion 33 of the barrel B. The upper end of the plunger G is formed with a head 34 of reduced 60 diameter that is adapted to fit within the lower end of the coiled expansible spring 35 mounted within the upper portion of the barrel B and confined therein by means of a screw plug 36. The plunger is bored transversely to receive a pin 37 which extends 65 not only through the plunger but through elongated slots 38 formed in the barrel B as shown in Figures 3 and 10. The opposite ends of the pin 37 are fixed within the reciprocating cam K' so that when vertically

moved, such movement will be imparted to the plunger G.

In the application of the hinge check to a door as shown in Figure 1, the inner edge of the door adjacent its lower end is recessed as indicated at 39 to accommodate the hinge check. The walls of this recess are covered by a metal strap 40 which carries the roller 19 and a bearing pin 41 which works in a suitable recess 42 formed in the plug 36. The lower end of the hinge check is secured to the floor by means of a floor plate P, suitable fastening members extending through the plate in the manner shown. The arm 16 is secured to the opposite sides of the door, while completely enclosing the hinge check is a housing H provided along its vertical edges with ears that receive fastening members for securing it in housing position with respect to the hinge check. For the proper operation of the hinge check, the upper inner corner of the door is provided with an angle plate 43 having a bearing 43^a in which works a bearing pin 44 carried by an angle plate 45 secured to the door casting. By this arrangement it will be seen that proper supporting means is formed for the upper end of the door to insure of the desired swinging movement.

The operation of the hinge check is as follows: With the door in the position shown in Figure 1, the roller 19 is at the apex or point of intersection of the cam surface 18, and when the door is swung in either direction to open position, the reciprocating cam K' is moved upwardly of the barrel B by virtue of the coaction of the walls of the helical grooves 17 of the cams K and K', the lower point of intersection of the upper walls of the grooves reposing within the recesses 17^a when the door has reached a 90° position. By virtue of this upward movement of the cam K', the guide plunger G is elevated against the tension of the spring 35 so as to effect a corresponding movement of the pistons T and T'. The container C is adapted to be partially filled with mercury so that upon upward movement of the pistons when opening the door such mercury will be drawn into the cylinders through the ports 26 and 26^a so that with the door in a 90° open position the cylinders are completely filled with mercury and the lower points of intersection of the upper walls of the grooves 17 repose within the recesses 17^a to temporarily maintain the door in open position. When it is desired to close the door a slight movement of the door will remove the points of the cam K' from the recesses 17^a to allow of the functioning of the spring 35 in depressing the plunger and the cam K' thereby causing the latter to coact with the cam K in returning the door to closed position. During this movement, the pistons T and T' descend into the cylinders 110 115 120 125 130

D and D' thus ejecting the mercury from the cylinders into the container. However, because of the restricted area of the ports 26 and 26^a, the flow of mercury from the cylinders is retarded thereby causing a retardation of the downward movement of the pistons into the cylinders and thus effecting a gradual and uniform closing of the door. This movement can be readily controlled by

10 an adjustment of the valve 27 which necessarily controls the flow of mercury from the cylinders.

Should the door be opened to any position less than a right angle position, and then released, there would be an insufficient quantity of mercury within the cylinders to effect and retard the closing of the door. However, in order to prevent such an action, the port 30 and the channel 31 are provided which, 20 because of their arrangement with relation to the cylinder D, permits of the rapid influx of mercury into this cylinder so that when the piston is moved outwardly to any distance greater than half of the length of 25 the cylinders, the port 30 will be opened thus allowing mercury to flow into the cylinder from the container. It will therefore be seen that a partial opening of the door will effect a partial filling of the cylinder D with 30 mercury, it having been found in practice that the partial filling of this one cylinder is sufficient to retard the closing movement of the door when the latter is moved to any position less than a right angular position.

35 Although I have herein shown and described only one form of hinge check embodying my invention, it is to be understood that various changes and modifications may be made herein without departing from the 40 spirit of the invention and the spirit and scope of the appended claims.

What I claim is:

1. A hinge check comprising, a rotatable cam, a reciprocating cam adapted to be elevated by the rotatable cam, a spring pressed plunger operatively connected to the reciprocating cam, and retarding means associated with the plunger to retard the downward movement of the reciprocating cam, 50 said retarding means comprising, a fluid container, cylinders within the container, pistons working within the cylinders and operatively connected to the plunger, and valve means for controlling the passage of the fluid in the container to and from the cylinders, said valve means including a port intermediate the ends of one of the cylinders, and a channel for effecting communication between the port and the container.

60 2. A hinge check comprising, a barrel, a rotatable cam and a reciprocating cam sustained on the barrel, a fluid container within the barrel, cylinders sustained within the container, ports and channels formed in the 65 cylinders at and above the lower ends of the

latter, pistons working within the cylinders, a plunger exteriorly of the container and operatively connected to the pistons, a spring for urging the plunger downwardly, and a pin carried by the plunger and operatively connected to the reciprocating cam in a manner to urge the cam downwardly with respect to the rotatable cam.

3. A hinge check comprising, a stationary sleeve, a cam rotatably mounted on the sleeve, a second cam super-imposed with relation to the first cam and adapted to be elevated by the latter, a barrel for sustaining the cams in position, a fluid container within the barrel, cylinders within the container 80 ports and channels for effecting communication between the container and the lower ends of the cylinders, a valve controlling said ports, a second port intermediate the ends of one of the cylinders, and a channel communicating with said second port for effecting communication between the cylinder and the container at a point above the cylinders, pistons working within the cylinders, a spring pressed plunger operatively connected to the pistons, and a pin for operatively connecting the reciprocating cam with the plunger.

4. In combination, a door and hinge check associated with the door and comprising a stationary floor plate, a stationary sleeve upstanding from said plate, a barrel secured to and upstanding from the stationary sleeve, a rotatable cam loosely encircling the barrel and supported upon the stationary sleeve, 100 said rotatable cam being rigidly connected with the door, ball bearings between said sleeve and said cam, a reciprocable cam loosely encircling the barrel and coacting with the rotatable cam, retarding means arranged within the barrel and operatively connected with the reciprocable cam, said reciprocable cam having shoulders and cam surfaces at its upper end, and a pin connected with the door and cooperable with the inclined surfaces and shoulder of the reciprocable cam.

5. In combination, a door and hinge check associated with the door and comprising a stationary floor plate, a stationary sleeve 115 upstanding from said plate, a barrel secured to and upstanding from the stationary sleeve, a rotatable cam loosely encircling the barrel and supported upon the stationary sleeve, said rotatable cam being rigidly connected with the door, a reciprocable cam loosely encircling the barrel and coacting with the rotatable cam, and retarding means arranged within the barrel and operatively connected with the reciprocable cam.

6. In combination, a door and a hinged check associated with the door and including a stationary sleeve, a barrel secured to and upstanding from the sleeve, a rotatable cam loosely encircling the barrel and sup-

ported upon the sleeve, said rotatable cam being rigidly connected with the door, a reciprocable cam loosely encircling the barrel and arranged above and cooperating with 5 the rotatable cam and retarding means arranged within the barrel and operatively connected with the reciprocable cam.

7. In combination, a door and a hinged check associated therewith comprising a stationary sleeve, a barrel secured to and up- 10 standing from the sleeve, a rotatable cam, loosely encircling the barrel and supported upon the sleeve, said rotatable cam being rigidly connected with the door, a reciprocating cam loosely encircling the barrel and arranged above and cooperating with the rotatable cam, retarding means arranged within the barrel and including a spring, a plunger coacting with the spring and a pin 15 secured to the plunger and the reciprocating cam, said barrel having elongated slots 20 accommodating the pin in its movements.

8. In combination, a door, and a hinged check associated with the door and com-

prising a stationary sleeve, a barrel secured 25 to and upstanding from said sleeve, a rotatable cam loosely encircling the barrel and supported upon the sleeve, said rotatable cam being rigidly connected to the door, a reciprocable cam loosely encircling the barrel 30 and arranged above and cooperating with the rotatable cam, a spring arranged in the upper part of the barrel and plunger coacting 35 with the spring, means for operatively connecting the reciprocable cam and the plunger whereby upward movement of the reciprocable cam is resisted by said spring, a fluid container arranged in the lower portion 40 of the barrel, cylinders within the container having ports and channels formed therein, rods depending from the plunger, pistons carried by said rods and adapted to operate in the cylinders and to partake of their downward stroke against the action of the fluid whereby downward movement of 45 the reciprocable cam is resisted.

GEORGE VUILLE.
